BROADBAND MICROWAVE WINDOW

John E. Burr, Jr., Wenham, Mass., assignor to Bomaic Laboratories Inc., Beverly, Mass., a corporation of Massachusetts

Application December 2, 1958, Serial No. 777,737

2 Claims. (Cl. 333—98)

The present invention relates to waveguide transmission apparatus and more particularly to an improved broadband non-resonant window for such apparatus and a novel method manufacture.

Prior art windows for use in waveguide transmission structures particularly at microwave frequencies generally comprise a metallic apertured frame with a dielectric enclosure sealed across the aperture. A metal alloy comprising iron, cobalt and nickel has proven extremely useful for glass-to-metal seals in view of a comparative thermal coefficient expansion between the two materials. The alloy referred to by the trademark Kovar has been widely adopted in fabricating such seals. The windows of the type to be described in the invention are widely used in microwave transmission lines to pressurize one section while an adjacent section is at atmospheric pressure. Such pressurization increase the power handling characteristics of the line by preventing arc-over and spitting at the high power levels. Furthermore, non-resonant windows are employed to provide a gas-retaining chamber where desired, as well as to prevent introduction of dust or humidity in the transmission path. It is desirable that such window structures cover a wide frequency band with a low voltage standing wave ratio and low insertion loss characteristic.

Recent developments in the art have evolved the use of mica window members sandwiched between metallic frame members for broadband transmission systems. An inherent disadvantage exists, however, in that mica splits very easily along the edges and the resultant windows will prove unsatisfactory for pressurization applications.

Accordingly, it is an object of the present invention to provide an improved broadband non-resonant waveguide window for microwave transmission systems.

It is a further object of the invention to provide an improved non-resonant window for waveguide transmission systems that is easy and less costly to manufacture.

Other objects, features and advantages will be evident after consideration of the following detailed description and the accompanying drawings, in which:

Figure 1 is an exploded perspective view of the illustrative embodiment;

Figure 2 is a perspective view of the assembled embodiment;

Figure 3 is a partial enlarged cross-sectional view of the embodiment along the line 3—3 in Figure 2;

Figure 4 is a perspective view of an alternative assembly partially broken away to reveal the dielectric member; and

Figure 5 is a partial enlarged detailed cross-sectional view along the line 5—5 in Figure 4.

Referring now to the drawings, the embodiment shown in Figure 1 is illustrative of a window configuration to be employed in the so-called ridge waveguide to transmit microwave frequencies of very wide band width. While this specific embodiment has been selected it will be realized that the invention will be equally applicable to all other transmission hollow-pipe line configurations

2

such as rectangular or circular. A front window frame 1 with suitable mounting holes 2 is provided with a substantially H-shaped aperture 3 having two reentrant central portions 4 and 5. The aperture dimensions will approximate the cross-sectional area of the inside of the hollow-pipe waveguide line and is, therefore, a non-resonant structure. A similar frame 6 with aperture 7 and reentrant portions 8 and 9 will serve as the back member of the assembly. In accordance with the teachings of

10 the invention window frames 1 and 6 will no longer be required to be fabricated from the alloy Kovar since a direct glass-to-metal seal has been eliminated. Instead, any desirable metal may be used including light weight aluminum which has a distinct advantage in air borne equipment.

The enclosure material in the embodiment comprises a dielectric material of thermoplastic resin composition namely polytetrafluoroethylene which is commercially available under the trademark Teflon. A sheet of this material having a bondable coating 12 on both planar surfaces prepared by the manufacturer by a surface etching process forms the window member 10. The window has the same outer dimensions as frame members 1 and 6. Mounting holes 11 mate with the frame holes to provide means for mounting the assembled structure in suitable waveguide apparatus. In order to provide efficient transmission of electromagnetic energy through the window assembly, the outer surface coating 12 is removed in the area 13 corresponding to the cross-sectional area of the inside of the selected waveguide line.

Surrounding the area 13, I provide a metallic interlacing in the form of wire stitching 14 extending through the window member 10 and following the same outline as the apertures 3 and 7. The stitching is located in the region between the edge of area 13 and the outer peripheral edge of the window member 10. It is desirable that good electrical continuity be provided between metallic frames 1 and 6 and, also the effect of the stitching on the overall voltage standing wave ratio measurement must be taken into consideration. After several sample pieces have been fabricated, the desirable location for the wire stitching will be determinable.

The complete window assembly is shown in Figure 2 and detailed in Figure 3. The overall assembly is formed simply by first coating the window member with a suitable epoxy resin to form layer 15 over all the areas surrounding the exposed area 13 including the stitching. Then the resin coating is cured in accordance with common procedure, either by heating or at room temperature as dictated by the resin material selected. The complete window assembly will now be ready for mounting in the waveguide transmission line between suitable flanges common in the art for pressurizing of systems or providing gas tight enclosures.

An alternative embodiment of the invention is shown in Figures 4 and 5 and comprises in this instance two metallic frames 16 and 17 having rectangular apertures 18 illustrated for the sake of clarity. The window member 19 in this embodiment is selected from a ceramic material with a conductive metallic coating 20 over both planar surfaces with the exception of the area 21 which corresponds to the apertures 18. A plurality of holes 22 are provided surrounding the area 21 prior to the application of the coating 20. As a result the coating will flow in the holes as at 23 to provide a metallic interlacing similar to the stitching in the previous embodiment. The window member 19 will now be sandwiched between the frames 16 and 17 and brazed together by the common ceramic-to-metal techniques including the molybdenum-manganese. The brazed metallic layer is indicated at 24 and unites the assembly into a composite unit.

The window assembly of the invention will be readily

adaptable to all waveguide type lines or other apparatus and excellent results have been attained with this non-resonant type structure. Minimum voltage standing wave ratios below those measured with conventional glass or mica prior art structures have been achieved together with accompanying low insertion loss measurements. Additionally, the metallic interlacing assures excellent electrical continuity heretofore attained only with metallic gaskets in glass structures and unattainable in mica structures wherein the mica is embedded in a glass frit mixture between the metallic frames.

Alternate embodiments, as well as modifications and variations will be readily apparent to artisans skilled in the art. It is my intention to cover such alterations, modifications and variations as fall within the spirit and scope of the invention as defined in the appended claims.

What I claim is:

1. A broadband non-resonant window assembly for hollow-pipe waveguide transmission apparatus comprising a window member of a thermoplastic resin material having a bondable coating on all planar surfaces with the exception of an exposed area equivalent to the inside wall dimensions of the hollow-pipe waveguide, a metallic interlacing disposed intermediate the edge of said exposed area and the peripheral edges of said window member and having substantially the same configuration as the hollow-pipe waveguide, a metallic apertured frame member secured to each planar surface of said window member by a bonding layer of an epoxy resin material to define a composite member adapted for mounting in suitable waveguide structure with said thermoplastic resin

material enclosing all of the inside cross-sectional area of said waveguide.

2. A broadband non-resonant window assembly for use in pressurized hollow-pipe waveguide transmission systems to seal separable sections, said window assembly comprising a member of a thermoplastic resin material having a bondable coating on all planar surfaces with the exception of an exposed area equivalent to the inside wall dimensions of the hollow-pipe waveguide, a continuous conductive wire interlacing surrounding the exposed area and having substantially the same configuration as the hollow-pipe waveguide, a pair of metallic frame members each defining a central aperture equivalent to the inside wall dimensions of the hollow-pipe waveguide, each of said frame members being secured to a planar surface of said thermoplastic resin member by a bonding layer of an epoxy resin material to define a composite member adapted for mounting between sections of hollow-pipe waveguide to provide a gas-tight joint with said thermoplastic resin member enclosing all of the inside cross-sectional area of said waveguide.
